UNITED STATES PATENT OFFICE.

FRANKLIN N. ISHAM, OF NEW LONDON, CONNECTICUT.

INTERNAL-COMBUSTION ENGINE.

1,184,242.

Specification of Letters Patent. Patented May 23, 1916.

Application filed April 25, 1913. Serial No. 763,682.

To all whom it may concern:

Be it known that I, FRANKLIN N. ISHAM, a citizen of the United States, residing at New London, in the county of New London and State of Connecticut, have invented certain new and useful Improvements in Internal-Combustion Engines, of which the following is a specification.

This invention relates to internal combustion engines.

The object which I have in view is to provide cylinders in an engine of the kind referred to, of such form as to be free from being rendered inefficient or useless as the result of being subjected to expansion and contraction due to the intense heat and rapid dissipation thereof incident to the operation of such engines.

With these objects in view the invention consists of a cylinder for internal combustion engines having the generic and specific features of construction and novel arrangement substantially as hereinafter described and claimed.

25 One form of embodiment of the invention is illustrated in the accompanying drawing in which is shown a vertical sectional view of an engine in which my improvements are incorporated.

30 The working parts of the engine are shown as assembled within and supported by a frame 1. Formed with the frame, or in a shell 2 attached thereto, at the upper end of the frame is an annular groove or seat.

35 The cylinder of the improved form consists of a portion 3 which is cylindrical in form and the wall of which is of a single and uniform thickness throughout and which has projecting from one end thereof an annular flange 4. This flange forms the only deviation from a cylindrical form involved in the portion 3, and therefore extensive expansion and contraction of the cylinder due to the high temperature and

40 rapid lowering of the same to which the cylinder of an internal combustion engine is subjected has no injurious effect. This is because the symmetrical form of the cylinder, the uniformity of thickness throughout the wall thereof, and the absence of protuberances subject to more rapid heating and cooling, insure uniform expansion and contraction throughout the entire part.

45 In order that the flange 4 may be maintained at a temperature practically uniform with that of the portion of the cylinder

der to which it is attached, the cylinder is surrounded by a jacket or shell within which is maintained a cooling liquid. To this end the inner face of the shell 2 is made 60 concave forming between the shell 2 and the cylinder a chamber 5 extending entirely around the cylinder, for containing a cooling liquid. The upper end of the chamber is formed by the flange 4 of the cylinder so 65 that the latter is constantly in contact with the cooling liquid. The lower end of the shell or water jacket has projecting from its inner face a flange 6 the edge of which is located a short distance from the face of the 70 cylinder permitting the cylinder to expand without contacting with the flange. In order to retain the liquid in the chamber, and also to permit the cylinder freely to expand, there is arranged in the edge of the flange a 75 packing 7 of some well-known yielding kind. If desired the upper portion of the cylinder may have applied thereto a strengthening jacket 8, such jacket being of uniform thickness throughout its walls. 80

The head 9 of the cylinder is attached to the jacket 2 by bolts 10, and the flange 4 of the cylinder is clamped between the head and the jacket. This securing of the flange constitutes the sole means of supporting 85 and retaining the cylinder in place, and thus any rigid securing means commonly employed in similar structures which would contact with the body of the cylinder and thus interfere with its equal longitudinal 90 or lateral expansion and contraction throughout are dispensed with. If it becomes necessary for any reason to replace a cylinder by another, it may be taken out by removing the head 9, withdrawing the cylinder and 95 introducing another in its place. This substitution may take place without disturbing the frame or any of the other operative parts of the engine. The piston employed in connection with the cylinder formed and mounted as described may be of any suitable form, but is preferably so constructed as to expand and contract if at all with uniformity in all the parts subjected to heat. 100

As herein shown that portion of the piston adjacent to the space in the cylinder in which the gas is ignited consists of a hollow body the walls of which are of uniform diameter throughout. Attached to the upper end of the piston and secured thereto 105 in any suitable way is a protecting plate 11 by which the heat of the ignited gas is pre-

vented from coming directly into contact with the wall of the piston. The upper end of the piston is reduced and surrounding the reduced portion are packing rings 12. Arranged in the hollow portion of the piston is a hollow shell 13 somewhat smaller in size than the interior of the body 10 of the piston, forming when the shell is arranged in the body a space 14 between the two parts for the introduction of a liquid for cooling the interior of the piston. The cooling liquid may be injected into the space 14 in any suitable way, as by means of a pump 15 communicating with the space, and the cooling fluid after circulating in the space may be drawn off through a discharge pipe 16 shown by dotted lines.

No claim is herein made to the construction of the piston or to the means for cooling the same as this will constitute the subject-matter of an application for patent to be made hereafter.

I claim:

1. An internal combustion engine comprising a cylinder of a uniform single thickness throughout having a flange extending from one end thereof, a support for the

cylinder having a water jacket formed therein, the parts being so arranged that one end of the water jacket is formed by the flange, and means for clamping the flange to the support.

2. An internal combustion engine comprising a cylinder of a uniform single thickness throughout and having a flange extending from one end thereof, a support for the cylinder having formed therein a water jacket which surrounds the cylinder, means for clamping the flange to the support in position to form one end of the water jacket, and a yielding packing interposed between the other end of the water jacket and the cylinder, the body of the cylinder being otherwise unconfined, whereby the cylinder formed as described is mounted in a manner to permit unobstructed uniform longitudinal and lateral expansion and contraction throughout.

In testimony whereof I affix my signature in presence of two witnesses.

FRANKLIN N. ISHAM.
